UNITED STATES PATENT OFFICE.

JOHN A. DIENNER, OF CHICAGO, ILLINOIS.

IRONING MACHINE.

Application filed September 15, 1921. Serial No. 500,778.

To all whom it may concern:

Be it known that I, JOHN A. DIENNER, a citizen of the United States, residing at Chicago, in the county of Cook and State of Illinois, have invented a certain new and useful Improvement in Ironing Machines, of which the following is a full, clear, concise, and exact description, reference being had to the accompanying drawings, forming a part of this specification.

The present invention relates to ironing machines, and has particular reference to a means and method for heating the same.

The heating of domestic ironing machines for household use presents one of the most difficult problems in the successful operation of these small ironing machines. In laundries where mangles of large capacity are employed, the mangles have skilled attention to insure the maintenance of a proper ironing temperature, and the ironing operation is usually continuous so that the heat is held at a substantially uniform point. In the case of the household ironing machine, however, the machine is subjected to the most unskilled attention, and frequently the ironing operation is irregular or interrupted so that the temperature of the heating surface fluctuates widely with the consequent possibility of scorching the clothes or not heating them enough. The tendency to overheat the ironing element is due primarily to the inability to successfully regulate the source of heat; and the tendency for the ironing surface to chill is due primarily to the lack of a stabilizing source of heat having sufficient reserve to carry over the period of high heat absorption. With either gas or electricity as the direct heating medium, automatic regulation is made difficult as it involves thermostats, valves, resistances, and other complicated apparatus, which should be avoided in any domestic ironing machine, owing to the cost of such apparatus and the unskilled attention available for its operation. It is also obvious that neither gas nor electricity has any thermal reserve for meeting fluctuating temperature demands at the ironing surface.

According to the present conception, I obviate these disadvantages by employing high pressure, high temperature steam as the heat transferring medium between a primary heating source, such as a gas burner or other source of heat, and the ironing surface, which may take the form of a roll, a

shoe or ironing surface of any form. The steam is generated in a compact high pressure boiler, forming part of a completely closed heat transferring circuit, which has 60 thermal connection with the ironing surface. By reason of the high pressure, high temperature characteristic of the system, the entire apparatus is of compact arrangement and of very small dimension, so that it can 65 be easily embodied in the structure or frame of the ordinary domestic ironing machine, whereby a unitary construction is obtained. The temperature of the steam is susceptible to easy regulation, this being preferably accomplished by control mechanism responsive to pressures in the circuit, inasmuch as the pressure and temperature of the steam and water confined in the closed heat transferring circuit has a high latent heat or 75 heat reserve which is always available for supplying an increased quantity of heat to the ironing surface upon fluctuations of temperature.

In the accompanying drawings illustrating a preferred embodiment of my invention:

Figure 1 is a front elevational view of a domestic ironing machine embodying my invention;

Figure 2 is a transverse sectional view through the ironing shoe and pad roller;

Figure 3 is a fragmentary elevational view of one end of the ironing shoe;

Figure 4 is a diagrammatic view illustrating the closed heating circuit, and showing the high pressure boiler unit in section; and

Figure 5 is a transverse sectional view through the ironing apparatus of a modified form of ironing machine illustrating a further application of my invention.

The ironing machine illustrated in Figure 1 is of any conventional construction. For the purpose of illustrating the present invention a form comprising a rotating padded roll and an arcuate heating shoe has been chosen, although, as will hereinafter appear, the present invention has application to other types of ironing machines as well. A horizontal table 7 is supported by end standards 8, and has rising from its upper surface end standards 9 for supporting a roll 11 and an ironing shoe 12. The padded roll 11 has its ends journaled in the end standards 9—9 and has any suitable driving connection broadly designated at 13 with an electric motor 14 or other suitable source of

power. The ironing shoe 12 is an arcuate casting having a polished ironing surface 15 embracing a considerable portion of the periphery of the padded roll 11. This ironing shoe is preferably rigidly supported between the end standards or brackets 9—9, the bearing supports for the padded roll 11 being preferably arranged to permit of its movement towards and away from the shoe 12, although this relation may be reversed, if desired, by arranging the shoe 12 for motion relative to the roll. The shoe casting in one form of the invention is provided with a plurality of longitudinally extending slots 16 which are grouped preferably equidistantly about the ironing surface 15 and are preferably extended substantially parallel for facility in inserting the heating coil which I shall now describe. Disposed in the bottoms of these slots are successive turns of the high pressure heating coil 18'. The several turns 18 of the coil lie in close proximity to the ironing surface 15 and have direct contact over a large portion of their area with the walls of the slots 16 for direct and rapid heat conduction to the ironing surface. After the insertion of the heating coil in the slots the outer surface of the shoe is preferably covered by a sheet metal covering 19, a filling material being inserted in the slots 16 on top of the pipes 18 if desired. It is desirable that the entire heating system be hermetically sealed, or as nearly so as possible, into a closed circuit, and to this end the several turns 18 of the heating coil 18' are integrally united, as by welding, at their ends, or by constructing the entire coil of a single piece of wrought steel tubing. The parallel arrangement of the slots 16 permits the several turns of the coil to be simultaneously inserted in the ironing shoe and thereby avoids the necessity of threaded end connections. The looped ends of the turns are preferably disposed in recesses 21 in the ends of the ironing shoe.

Instead of a single continuous length of tubing, a plurality of tubes may be arranged in parallel, as shown in diagrammatic form in Figure 4. In this arrangement the heating coil or element comprises the upper and lower headers 20—20' and the transverse tubes 30.

The boiler is designated 22 in its entirety and is located on a shelf as extending longitudinally between end standards 8—8 below the table 7. The boiler 22 is preferably constructed in accordance with the teachings of Patent Number 1,236,641 issued to William H. Winslow, and comprises one or more individual water tube sections, one of which is shown in elevation in Figure 4. Each section comprises a pair of vertical risers or headers 24 and 25 which are connected by transverse tubes 26 that have their ends welded by autogenous welding to the headers 24 and 25. The transverse tubes 26 preferably have a greater inclination at the lower ends of the headers 24 and 25 than they have at the upper ends of said headers, and to this end the front header 24 is made of less length than the rear header 25. The transverse tubes are preferably slightly bowed in the plane of the section to relieve stresses which might be induced by unequal expansion. The boiler is built up of one or more sections and these sections are connected by short tubes 27 and 28 to the upper and lower transverse headers 29 and 31 respectively. These short tubes 27 and 28 are welded to the sections and to the respective headers in order to secure an absolutely tight joint.

The boiler is enclosed by a cast iron casing or housing 32 which is preferably composed of two halves fastening together by suitable flanges and bolts 33. This affords convenient access to the boiler sections. The lower end of the casing 32 forms a suitable fire box 34 into which projects the fuel burner 35 and the small pilot burner 36. Each section of the boiler is provided with a suitable baffle member 37 secured to the transverse tubes in order to define a passage for the fire gases from the fire box 34 upward to heat intensely the lower right hand corner of the boiler, as viewed in Figure 4. The casing 32 is spaced away from the front headers 24 of the boiler to define a flue passage 38 communicating at its lower end with the fire box 34 and at its upper end with the space 39 which is provided between the top of the casing 32 and the top of the boiler. The headers 24 and 25 are in contact with the side walls and are of greater diameter than the transverse tubes 26 so that they define walls substantially impervious to the passage of gases. The space 39 is closed off at the rear of the boiler by means of the wall 41 which compels all the gases to pass downward between the baffle wall 37 and the wall formed by the rear risers 25 and below the lower left corner of the boiler as viewed in Figure 4. From this point the gases ascend through a smoke flue 42 which is led vertically to a point above the height of the machine and above the height of the operator so as to emit the gases of combustion into the upper part of the room. If desired this flow could be connected to discharge externally, although it should be noted that this is not necessary as the gases discharged from the boiler are no more obnoxious than those from the ordinary gas burner which is usually incorporated in the ironing shoe. The inner walls of the casing 32 adjacent to fire box 34, the flue 38 and the upper space 39 are lined with a suitable refractory material 43 to protect the casing from the action of the heated gases.

In the form of the heating coil chosen in Figures 2 and 3 both ends of the tube forming the heating coil 18' are led down to the boiler 22, the end which communicates with the upper part of the coil being united to the end of the transverse steam header 29, and the other end which connects with the lower part of the heating coil being united to the end of the lower water header 31. These connecting portions of the tube can be covered with asbestos or other suitable heat insulating material 40. In the form of heating element 18' shown in Figure 4 the upper header 20 is connected with the steam header 29 by way of pipe 44 and the lower header 20' is connected by the water header 31 by way of pipe 45. The burners 35 and 36 are supplied with a suitable fuel, preferably gas, from a main 46 under the control of a pressure responsive valve 47 which operates to graduate the amount of fuel gas supplied to the burner. The pilot burner 36 is connected by a separate pipe 48 with the supply pipe 46 anterior to the valve 47 and is maintained constantly burning while the ironing machine is in operation. The pressure responsive valve 47 is of any conventional design and is controlled by a diaphragm which is proof against the high temperatures and pressures prevailing in the heating circuit. The diaphragm chamber 49 is provided with a union or fitting 51 which may have through threaded connection in the end 45 of the heating coil, or which may be welded into an integral unit with the adjoining portions of the tube 45, as illustrated, for maintaining a hermetic seal throughout the circuit. The diaphragm is illustrated at 50 and it will be noted that it is shown as being of metal and welded integrally to the flange of the chamber 49. As illustrative of this practice it has been demonstrated that successful metal diaphragms for the present pressures and temperatures can be made of "Monel" or "Aterute" metals, and these can be successfully welded to a metal support or housing such as the fitting 51. Any conventional arrangement of spring and stem 52 may be arranged for controlling the motion of the diaphragm in the diaphragm chamber 49 and for transmitting this motion to the burner regulating valve 47.

Any suitable adjustment may be provided in the control apparatus for regulating the normal temperature prevailing at the ironing surface 15. In the embodiment illustrated I have shown this as being accomplished by a hand wheel 53 which moves up or down on a thread on the end of the diaphragm stem 54 for regulating the compression of the spring 52. By turning this hand wheel up or down the steam pressure is made operable to reduce the gas supply at a lower or higher point and thereby vary

the mean temperature at the ironing surface 15. For filling the system there is preferably extended a small pipe 55 from the uppermost point of the heating coil 18' to serve as an air trap. As any air that might accidentally be contained in the system would, under the very high pressure which is maintained in the boiler, occupy a small space, it is apparent that very little room in the air trap 55 is necessary to contain such entrained air. The pipe 55 may be plugged or hermetically sealed after the required amount of fluid has been inserted in the system. Water is not the sole liquid which can be employed in the present system as it may be found desirable to employ mercury or any other liquid having desirable characteristics as the vaporizable medium in the boiler.

The level of the liquid in the boiler stands normally less than half way up the risers 24 and 25 whereby a fairly large space is provided in the upper parts of the risers and the upper transverse tubes 29 for heating and drying the steam as it is evolved. Inasmuch as this system comprises a closed circuit the level of the liquid need not be particularly determined and it is immaterial whether the same be slightly higher or lower than above mentioned. The safety of the boiler is noteworthy. The boiler and all parts under pressure are constructed of tubes of relatively small size capable of withstanding great pressures. In the transfer of heat from the boiler to the heating coil 18' the latent heat in the condensation of the steam or vapor makes possible the transfer of heat with a relatively small quantity of the transferring medium. This also makes possible the transfer of heat in considerable quantity without change of temperature. The diaphragm chamber 49 and the gas regulating valve 47 co-operate to maintain a practically uniform pressure in the system and thus operate to maintain a constant temperature at the ironing surface 15. The coil or tubing 18' is, in each instance, arranged to drain the condensate back to the boiler.

By the use of saturated steam at a pressure corresponding to the desired temperature for ironing a peculiarly even heat first along the length of the ironing shoe, i. e., longitudinal distribution along the shoe and next, a remarkably even heat from time to time regardless of the rate at which articles are ironed, may be maintained.

There is no tendency for the shoe to develop a hot spot or a cold spot, as is the case with present domestic ironing machines when a gas flame is applied directly to the shoe. This is because the saturated steam tends to condense and give up its latent heat of vaporization at the coldest point on the shoe. The action is, therefore, selective in applying the heat precisely where needed.

There is no tendency for the shoe to get too hot when ironing is interrupted, as is the case with gas heated shoes of the prior art, because the steam will not give off any more heat after the shoe attains the temperature of the steam. Any further heat applied to the boiler by the burner at this time will tend to evaporate more water and raise the temperature of the steam in the system. This results at once in a closing of the gas valve 47 and reduction of the rate of burning gas under the boiler.

If now the shoe is called upon suddenly to iron a large piece of fabric containing considerable moisture, the demand for heat is abnormal and tends to chill the shoe. However, the heat reserve contained in the steam and in the water in the boiler is instantly available to prevent such chilling and, at the same time, any reduction in pressure caused by sudden abstraction of heat from the shoe results in evolution of steam from the water in the boiler and, at the same time, results automatically in opening of the gas valve and increased fire under the boiler.

The system is designed as aforesaid to carry great pressure, such as is required in the case of saturated steam, to maintain a temperature suitable for ironing the family wash, which includes starched goods.

In Figure 5 I have illustrated a modified adaption of my invention to a form of ironing machine employing a convex instead of a concave ironing shoe 12". Two padded rolls 57 and 58 co-operate at top and bottom respectively with a convex ironing shoe 12', both rolls being driven from a central power gear 59 connecting through chains 60 with sprockets 61 and 62 on the axes of the rolls. The sprockets 61 and 62, or the rolls 57 and 58, or both, are preferably proportioned whereby the lower roll 58 revolves at a slightly higher peripheral speed than the roll 57 in order to stretch

the fabric being ironed across the surface of the shoe 12". In this embodiment I have shown the arrangement of heating coil illustrated in Figure 4. The upper and lower headers 20 and 20' are extended longitudinally of the ironing shoe in slots 40, and the cross tubes 30 are set into transverse slots 50. These slots are covered by a plate 19" and may be filled if desired after the insertion of the coil. This coil is connected with a boiler, as 22, and the general operation of this embodiment is substantially the same as above described. The heating coil is preferably made of seamless steel or copper tubing.

I claim:

In an ironing machine suitable for domestic use, the combination of an ironing shoe, an ironing roller co-operating therewith, a boiler below the shoe, said boiler having a fixed charge of water partially filling the same, a heater for the boiler, a control member therefor, a heat radiating pipe, disposed in thermal contact with the shoe and arranged to be self draining, a steam supply pipe connecting the boiler to the upper end of said heat radiating pipe, a condensate return pipe connecting the lower end of the radiating pipe to the boiler for draining the condensate by gravity to the water space of the boiler, said boiler, said heat radiating pipe, and said connecting pipes being connected freely together and hermetically sealed to prevent loss of the fixed charge of water, and a pressure responsive element governed by the pressure of the saturated steam in said closed system to control the heater control member, said pressure responsive element being adjusted to maintain the shoe at a temperature suitable for ironing starched goods.

In witness whereof, I hereunto subscribe my name this 10th day of Sept., 1921.

JOHN A. DIENNER.
